(57) **CLAIM**

The ornamental design for a display screen with an animated graphical user interface, as shown and described.

DESCRIPTION

FIG. 1 is a front view of a first embodiment of a first image of a display screen with an animated graphical user interface showing our new design;

FIG. 2 is a front view of a second image thereof;

FIG. 3 is a front view of a third image thereof;

FIG. 4 is a front view of a fourth image thereof;

FIG. 5 is a front view of a fifth image thereof;

FIG. 6 is a front view of a sixth image thereof;

FIG. 7 is a front view of a seventh image thereof;

FIG. 8 is a front view of a eighth image thereof;

FIG. 9 is a front view of a second embodiment of a first image of a display screen with an animated graphical user interface showing our new design;

FIG. 10 is a front view of a second image thereof;

FIG. 11 a front view of a third image thereof;

FIG. 12 is a front view of a fourth image thereof;

FIG. 13 is a front view of a fifth image thereof;

FIG. 14 is a front view of a sixth image thereof;

FIG. 15 is a front view of a seventh image thereof; and,

FIG. 16 is a front view of a eighth image thereof.

The appearance of the image transitions between the images shown in FIGS. 1-8 and 9-16. The process or period in which an image transitions to another forms no part of the claimed design. The broken lines depicting the display screen or portion thereof form no part of the claimed design.
